UNITED STATES PATENT OFFICE.

WILLIAM H. BLAKE, OF JERSEY CITY, NEW JERSEY.

PENCIL.

1,204,336.

Specification of Letters Patent. Patented Nov. 7, 1916.

Application filed November 11, 1913. Serial No. 800,255.

To all whom it may concern:

Be it known that I, WILLIAM H. BLAKE, a citizen of the United States of America, residing at Jersey City, in the county of Hudson and State of New Jersey, have invented certain new and useful Improvements in Pencils, of which the following is a specification, reference being had to the accompanying drawings.

10 This invention relates to improvements in pencils and particularly to improvements in pencils in which the lead is fed by mechanism from time to time as the wearing away of the lead may require; and an object of 15 this invention is to provide a pencil of the type just referred to which will be simple in construction, comparatively cheap in manufacture and efficient and durable in operation and use.

20 Another object of this invention is to provide a pencil of the character just set forth with mechanism by which the lead will be firmly gripped and which may be released to permit the free feeding of the lead.

25 A third object of this invention is the provision in a pencil of the character hereinbefore described of means for holding the lead-feeding mechanism normally inoperative.

30 A fourth object of this invention is to provide a pencil of the kind hereinbefore mentioned which may be readily assembled and dismantled.

35 A fifth object of this invention is to provide with a receptacle for spare leads a pencil in which the lead is mechanically fed.

40 A sixth object of this invention is the provision in a pencil of the character hereinbefore referred to with novel means for housing a suitable pencil-sharpener.

45 Other features of my invention will be set forth in the description and claims which follow hereinafter.

50 In the drawings illustrating the principle of this invention and the best mode now known to me of applying that principle, Figure 1 is a central longitudinal section through my new pencil; Fig. 2 is a similar section through the front or pencil end; Fig. 3 is a section on the line A—A of Fig. 1; Fig. 4 is a detail showing the casing extension and the lead-feeding spindle; Fig. 5

is a detail showing the connection-piece; Fig. 6 is a detail showing the eraser ends of the jaw-carrying guide-tube and its enclosing sheath; Fig. 7 is a detail showing in plan the jaw-carrying guide-tube, the sheath mounted thereon and the lead-holder arranged therein; Fig. 8 is an end view of the pencil-sharpener; Fig. 9 illustrates a modified form of this invention, parts being broken away to disclose the interior construction; Figs. 10 and 11 show in elevation the clutch-members; Fig. 12 illustrates another modified form of this invention, parts being broken away for the sake of clearness in illustrating the interior parts; Fig. 13 is a detail illustrating the lead-holder with the lead mounted therein; and Fig. 14 illustrates a modification hereinafter referred to.

70 The central body portion *a* of the casing is formed with a reduced exterior-threaded projection at each end. Upon the reduced threaded projection *a'* at the front or writing end there is screwed a hollow conical-shaped nose-piece *b* provided with a substantially cylindrical bushing *c*; and upon the reduced threaded portion *a''* at the butt or eraser-end there is screwed a casing extension-piece or tailpiece *d* which is in the form of a cylinder closed at one end *d'* and having in the latter a central opening *d''*. Between the front end of the exterior-threaded projection *a'* and an annular shoulder or ledge *b'* formed upon the interior of 80 the nose-piece *b* there is provided a cup-shaped bushing *e* formed with a central aperture *e'* in its base *e''*. Within the body *a* of the casing there is mounted a guide-tube *f* the enlarged front-end of which is 85 split to form spring-jaws *g*, the base *g'* of which jaws slopes rearwardly and inwardly toward the tube *f* so that this base *g'* is conical in shape and forms an enlargement upon the front or writing end of the guide-tube *f*. 90 The jaws *g* are formed with lips *g''* which grip the lead *h*. The guide-tube *f* is incased in a tubular sheath *h* of sheet-metal (or other suitable material); and at its front end this sheath is provided with a collar *i*. 100 The jawed guide-tube *f* is formed with a lengthwise-extending slot *f'* and the sheath *h* is likewise formed with a similar slot *h'*; and normally these slots *f'*, *h'*, are in reg-

- ister with each other. The edge portions h'' of the walls of the slot h' are doubled back or folded inward on themselves (Fig. 3) to form guideways or guide-channels h'' in which are held frictionally the edge portions f'' of the walls of the slot f' , so that the guide-tube f and its sheath h normally move together both lengthwise and rotatably.
- 10 Between the collar i and the base of the cup-shaped bushing e there is interposed a coil-spring j which normally presses the tubular sheath h (and through it the jawed guide-tube f) rearwardly or inwardly toward the eraser-end of the pencil, whereby the conical base g' of the jaws g is caused to bear or rub against the annular wall at the mouth or front end of the bushing e . Thus there is produced a cam action between
- 15 the sloping base g' of the jaws g and the mouth of the bushing e , whereby the spring-jaws g are closed toward each other so as to cause the lips g'' to grip firmly the lead k . The lead k is carried by a lead-carrier m
- 20 the front end of which is forked or formed with a recess m' adapted to receive the flattened butt end m'' of the lead, while the heel end of the lead-carrier m is formed with a pair of laterally-extending lugs m''' that
- 25 project normally through the slots f', h' of the guide-tube f and its sheath h and engage a thread α' formed upon the interior of the body a of the casing. It is obvious from this construction that, if the lead-carrier m be
- 30 turned relatively to the body a , the engagement of the lugs m''' with the thread α' will cause lengthwise movement of the lead-carrier and, therefore, of the lead k itself. The lead-carrier m is turned by turning the
- 35 tubular sheath h , through the slot h' in which project the lugs m''' ; and the guide-tube f , together with its sheath h , is turned through the agency or medium of a multi-part spindle n . The rear end of this spindle
- 40 is in the form of a clutch-member o which is hollow and, at its rear end o' , is threaded and, at its front end, is formed with a head o'' slotted longitudinally at α'' .
- 45 Between the threaded end o' and the slotted head o'' there is formed upon the clutch-member o a boss p having clutch-fingers p' which extend lengthwise and rearwardly. The interior of the socket-like extension d of the casing is formed with a number of
- 50 longitudinal grooves q between which are ribs q' ; and the clutch-fingers p' are adapted to enter the grooves q and engage normally the ribs q' , whereby the clutch-member o and the casing-member d will be
- 55 normally clutched together or interlocked.
- 60 Between the clutch-member o and the guide-tube f there is interposed the front part of the spindle n , viz., a connection-piece r having at each end a reduced projection

formed with a laterally-extending stud. 65 The rear projection r' is adapted to enter a recess α'' formed in the head o'' of the clutch-member o , whereupon the stud r'' engages in the lengthwise-extending slot α' formed in the head o'' . The front projection r'' of the connection-piece r is adapted to engage in the rear end of the guide-tube f , whereupon the stud r'' engages in a recess or notch f'' formed in one of the walls of the slot f' . The stud r'' in this position engages also in the notch h'' formed in the rear end of the tubular sheath h . Upon the projecting threaded end o' of the clutch-member o there is screwed a hollow cup-shaped nut s within the lateral wall s' of which fits slidably and snugly the rear or base end d' of the casing-extension d ; and this nut s is normally locked in place by the lock-nut t on the threaded end o' .

From the foregoing description it will be 85 obvious that the coil-spring j normally maintains the clutch-member o in clutching engagement or interlocked with the casing-member d so that relative rotation of the spindle n and its connected guide-tube f 90 is normally impossible. When, however, it is desired to feed forward the lead k , the operator presses forwardly the cup-shaped nut s whereby the spindle n is pushed lengthwise toward the writing end 95 of the pencil and the clutch-fingers p' are disengaged from the ribs q' of the casing-member d , whereupon the spindle n , the sheath h , the guide-tube f , and the lead-carrier m may be turned relatively to the 100 casing; and, as hereinbefore explained, such relative rotation results in feeding forward the lead-carrier m and the lead k carried by it. It is, however, to be particularly observed that the pushing forward of the 105 cup-shaped nut s also serves to move lengthwise the jaws g so that the latter are forced outwardly beyond the mouth of the bushing e ; and, being thus released, they fly apart by their own resiliency, so that the lead k is released and is free to be moved lengthwise. Therefore, during the rotation and feeding outwardly of the lead k , the same is released entirely from the gripping action of the jaws g .

115 In the modified form shown in Figs. 9 to 11, both inclusive, the pencil is operated by pushing forward the nut s , in substantially the same manner as in the case of the pencil illustrated in Fig. 1, although the 120 mechanism is somewhat different. The spindle n' is formed at its front end with a clutch-member n'' with which co-operates the clutch-member n''' detachably connected with the guide-tube f and its sheath h by 125 a stud r'' in the same manner as that in which the connection-piece r is connected at its front end to the corresponding elements

- of the structure illustrated in Fig. 1. The clutch-members n'' , n^* are maintained normally separated by a coil-spring u and the spindle n' is formed with a collar n^* which 5 bears normally against the base-end d' of the casing-extension piece d^* . It will be obvious that the spindle n' may be normally turned without in any way affecting the position of the jaws g or the lead k ; but 10 when it is desired to feed the lead k forward, the user pushes the nut s forward along the casing-extension piece d^* until not only the rib w on the clutch-member n^* engages in one of the grooves w in the front 15 clutch-member n'' but also the jaws g have been thrust forward a distance sufficient to permit them to spring apart and release the lead k . The user then turns the nut s and thereby feeds the lead k forward, the mechanical 20 operation being the same as that already explained in connection with the description of the pencil shown in Fig. 1.
- In Fig. 12, there is illustrated a modified form which operates just the reverse of the 25 form shown in Fig. 1; that is, the spindle x and its connected parts are pulled rearwardly instead of being pushed forwardly. In this modified form it is the front part g^* of the jaws which bear against the mouth 30 of the nosepiece c ; and, since this front part g^* of the jaws slope inwardly toward the front, the lead k is relieved from the gripping action of the latter when they are withdrawn within the nosepiece c . In rear of 35 the base of the jaws there is formed a collar y against which bears the front end of the coil-spring j whereby the jaws g^* are pressed against the interior of the nosepiece c and thereby forced toward each other so as to 40 grip the lead k firmly. The spindle x is one-piece and its front end is formed with a stud r^* which engages in a notch f^* in the guide-tube f and in a notch h^* in the tubular sheath h in just the same way as the stud 45 r^* of the front end of the connection-piece r is joined or attached to the guide-tube f and its tubular sheath h in the form illustrated in Fig. 1. The rear end of the casing-extension member d^* is formed with a 50 cavity or socket z the lateral wall of which is grooved interiorly and formed with lengthwise-extending ribs q' between the grooves q . The spindle x is formed at its rear end with a boss p^* having clutch-fingers 55 p'' which extend lengthwise and forwardly and normally engage between the ribs q' , whereby the casing-extension d^* and the spindle x are clutched together or interlocked normally. Upon the threaded end 60 o'' of the spindle x there is mounted a cup-shaped nut s and a lock-nut t . By pulling to the rear upon the nut s (or its lock-nut t), the spindle x is drawn to the rear against the tension of the coil-spring j and the clutch-fingers p'' are disengaged from the 65 ribs q' , whereupon the spindle x is now free to be rotated. When the spindle x is drawn to the rear, as just described, the jaws g^* are drawn inwardly and within the nosepiece c and are thereby released from the 70 confining action of the latter, whereupon the jaws g^* now spring apart and release the lead k , so that the same may be turned free from the gripping action of the jaws.
- Upon the threaded rear end o' of the spindle n there is screwed a lock-nut t the rear end of which is reduced and exteriorly threaded. Upon this reduced threaded rear end t' there is screwed a carrier member 2 each end of which is formed with a socket. 75 In the front socket $2'$ there is screwed a pencil-sharpener 3 comprising a plurality of three-sided pyramidal cutters 4 the cutting edges $4'$ of which closely approach each other in passing from the outer end to the inner end 80 of the sharpener (Fig. 8). When the lead k needs sharpening, the user unscrews the carrier device 2 and, placing the end of the lead to be pointed in the sharpener 3 , turns the lead and the latter relatively to each 85 other. Since the butt end m^* of the lead k is flattened, the lead will be held against turning during sharpening with the sharpener 3 .
- In the rear socket $2''$ of the carrier device 2 there is inserted a rubber eraser 5 . The cylindrical wall 6 of this rear socket $2''$ is slotted (as at $6'$) and is reduced and threaded exteriorly at its rear end $6''$ which is formed with a beveled face 6^* at its outer 90 extremity; and upon this exteriorly-threaded rear end $6''$ there is mounted a nut 7 the interior of which is formed with a beveled face 7^* that co-acts with the beveled face 6^* formed on the socket $2''$. By screwing up 95 the nut 7 the annular cam face 6^* travels over the annular cam face 7^* and the wall $6''$ is made to grip or pinch the eraser 5 , whereby the latter is held firmly. By unscrewing the nut 7 , the eraser is released and 100 may be fed outwardly in order to compensate for wear.
- It is to be observed that the lock-nut t is normally kept tightly screwed against the nut s , since in the operation of feeding forward the lead, it is obviously necessary that the nuts s , t , be not rotatable upon the threaded end o' of the spindle n . However, when it is desired to take the pencil apart for any purpose, the nut s is unlocked by 115 turning the lock-nut t in the proper direction. The threaded eraser-end o' of the spindle o is hollow and is thereby adapted to act as a receiver k' for extra leads. This receiver k' is normally closed by the lock- 120 nut t (Fig. 1).
- It may be further observed that the connection piece r is provided for the purpose

of making the assemblage of the parts of the pencil easier. The guide-tube *f* is slidably fitted in its sheath *h* so that it may be forcibly pulled out of the latter for purposes of repair or replacement; but the guide-tube is so held frictionally in the sheath *h* that in the normal operation of the pencil, the guide-tube *f* and its sheath *h* move both rotatably and longitudinally together. It is further to be noted that during the feeding forward of the lead, the lips *g* do not bear at all upon the lead, which feature results in less stress being thrown upon the brittle lead and permits the lips *g* to clamp with great firmness the lead when the parts are in the ordinary writing position.

So far as known to me, I am the first to provide a pencil in which the lead-gripping mechanism, which normally hold the lead firmly, is released during the feeding of the lead.

In accordance with the provisions of the patent statutes, I have described the principle of operation of my invention, together with pencils which I now represent to be the preferred embodiments thereof; but I desire to have it understood that the pencils shown are only representative and that the invention may be carried out by other means. Thus, the interior of the casing may be left smooth and free from parts which would interlock with the lead-feeding mechanism (Fig. 14) so as to maintain the latter normally locked or inoperative; and other means than those herein shown and described may be provided for releasing the grip of the jaws upon the lead and feeding the same lengthwise.

40 I claim:

1. A pencil including a casing; lead-gripping jaws; a lead-holder; lead-holder-feeding mechanism; and means for releasing the grip of said jaws upon the lead, when said lead-holder is out of engagement with said jaws; said means being arranged to actuate said lead-holder-feeding mechanism.

2. A pencil including a casing formed with a nose-piece; yielding lead-gripping jaws normally held in gripping position by said nose-piece; lead-holder feeding mechanism; and means by which said jaws are moved relatively to said nose-piece and are disengaged from the casing and permitted to spring apart, when said lead-holder is out of engagement with said jaws; said means being arranged to actuate said lead-holder-feeding mechanism.

3. A pencil including a slidable guide-tube formed with lead-gripping jaws; a casing the pencil end of which presses said jaws into gripping position; a lead-holder which is carried by and slidably relatively to said guide-tube and is in engagement

with said casing; and means by which said guide-tube is moved lengthwise relatively to said casing to disengage said jaws from said casing and thereby to permit said jaws to spring apart, when said lead-holder is out of engagement with said jaws; said means being arranged to turn said lead-holder relatively to the casing and thereby to feed the lead-holder.

4. A pencil including a casing; lead-gripping jaws; a lead-holder; lead-holder-feeding mechanism; means for maintaining said mechanism inoperative; and mechanism for releasing the grip of said jaws upon the lead and actuating said lead-holder-feeding mechanism.

5. A pencil including a casing; lead-gripping jaws; a lead-holder; lead-holder-feeding mechanism; means by which said mechanism is interlocked with said casing to maintain said mechanism normally inoperative; and mechanism for releasing the grip of said jaws upon the lead and actuating said lead-holder-feeding mechanism.

6. A pencil including a casing; a rotatable lead-holder movable lengthwise relatively thereto and in engagement therewith; and means for turning said lead-holder to feed the same, said means including a spindle formed with a socket for the reception of spare-leads and a closure for said socket, said closure being readily removable to permit access to be gained freely to the spare leads within said socket.

7. A pencil including a casing; a lead-holder in engagement therewith; means including a spindle and a nut mounted thereon for turning said lead-holder to feed the same, said spindle being formed with a socket for the reception of spare leads; and a lock-nut which locks said nut on said spindle and closes the socket formed therein.

8. A pencil including a casing; lead-gripping jaws; a lead-holder; a spring for maintaining said casing and jaws in engagement and said jaws closed upon the lead; and mechanism for disengaging said casing and jaws and feeding said lead-holder.

9. A pencil including a casing formed with a nose-piece; yielding lead-gripping jaws normally held in gripping position thereby; a lead-holder; a spring for maintaining said casing and jaws in engagement and said jaws closed upon the lead; and mechanism for disengaging said casing and jaws and feeding said lead-holder.

10. A pencil including a slidable guide-tube formed with lead-gripping jaws; a casing the pencil end of which presses said jaws into gripping position; a lead-holder which is carried by and slidably relatively to said guide-tube and is in engagement with said casing; a spring for maintaining

said casing and jaws in engagement and said jaws closed upon the lead; and mechanism for moving said guide-tube lengthwise to disengage said jaws and casing and for 5 turning said guide-tube to feed said lead-holder lengthwise.

Signed at the borough of Manhattan, city,

county, and State of New York, this seventh day of November, 1913, in the presence of the two undersigned witnesses.

WM. H. BLAKE.
